ACOUSTICAL MATERIAL

Frank J. Taforo, Jr., San Francisco, Calif.

Application August 9, 1941, Serial No. 406,230

10 Claims. (Cl. 20—4)

The present invention relates to acoustical materials and more particularly to a combination of substances having desirable acoustical qualities with other substances having desirable structural qualities and appearance.

One type of acoustical material in general use consists of mineral wool or other fibrous or porous substances having a high coefficient of sound absorption concealed in metal pans by means of which it is supported and attached to the surface to be treated. The metal pans are perforated to admit the sound to the substance which they conceal, but present a sufficient hard smooth surface for convenience in painting and cleaning in the manner of an ordinary wall or ceiling surface. This material is applied in small sections over the surface of a complete ceiling. It is not itself adaptable to permanent ceiling construction and, therefore, adds greatly to the cost of the interior with which it is used. It is also undesirable in that it is applied in small sections or square tilelike members which present unsightly and undesirable crevices at their abutting edges.

It is the object of the present invention to provide a material having good acoustical properties and a smooth exposed surface and which may be used structurally as an integral part of the surface which it forms.

A further object of the invention is to provide an acoustical material, the principal structural portion of which is in the form of a metal lath adapted to be applied over metal or wood joists or other structural forms and adapted to receive a coating of plaster which covers up certain perforated portions of the metal lath behind which is concealed a sound absorbent material.

One form of the present invention is exemplified in the accompanying drawings to which detailed reference is made in the following specification, wherein further objects and advantages of the invention are made apparent.

In the drawings:

Fig. 1 is a perspective view of an acoustical material embodying the present invention applied to a ceiling and cut away to expose a transverse section thereof;

Fig. 2 is a longitudinal sectional view taken mainly along the line II—II of Fig. 1 and broken away to expose a section through a receptacle containing mineral wool;

Fig. 3 is a view like Fig. 1 illustrating means for attaching the acoustical material to wooden joists;

Fig. 4 is a perspective view of a portion of the

metal part of the acoustical material illustrating the construction at the end of a sheet by means of which it may be attached to an adjacent sheet; and

5 Fig. 5 is a plan view of a sheet of the metal used in the acoustical material.

In the following description, the present invention is disclosed as formed principally of sheet metal, rock wool and plaster. These materials 10 are, however, referred to in the specification to exemplify any similar or equivalent substances. For example, the sheet metal may be replaced by any relatively rigid material suitable for the purposes described and the term rock wool is used 15 to signify any one of a large class of porous or fibrous materials known to have the quality of absorbing rather than reflecting sound.

Referring to the drawings the invention is shown as comprising a sheet generally indicated 20 at 10 of metal or other relatively rigid material. This sheet is bent or formed to provide alternately arranged parallel channels and ridges. The surfaces of the ridges which are to be exposed are shown at 11 and are all formed on a common 25 plane so that the channels may be filled with plaster as shown at 12 finished to the same level. In the operation of applying the plaster the ridges are used as screeds to aid in forming a perfect smooth, planar surface over the entire area of the material.

The reverse sides of the ridges, which are the upper sides when the material is applied to a ceiling as illustrated, form elongated receptacles 30 for pads 13 of rock wool and these pads are preferably supported in spaced relation to the surfaces 11 which are perforated as indicated at 14 to admit sound to the receptacles containing the acoustic pads. The spacing between the perforated surface 11 and the rock wool has certain 35 acoustical advantages and makes it possible to wash or paint the exposed surface of the material without moistening or otherwise effecting the rock wool. The number, size and spacing of the perforations 14 is determined by the best practice and does not constitute a part of the present invention.

The preferred manner of supporting the acoustical pads in spaced relation to the surfaces 11 is by forming the pads with chamfered edges as shown so that they will register with angularly disposed portions 15 of the side walls of the receptacles in which they are disposed. The pads are usually covered with a very light muslin which does not interfere with their sound absorbing

properties but which serves to preserve their shape and prevent deterioration.

The upper portions of the receptacle walls are, as shown at 16, disposed at right angles to the surfaces 11 and the backs of the plaster channels are re-entrant to form a shallow plaster space and to form walls 17 which cooperate with the portions 16 to form a rigid partition between adjacent sections of the material. The re-entrant backs of the plaster channels have bottoms 18 which are provided with relatively large spaced perforations 19 through which the plaster flows when it is applied so that it is securely keyed to the metal in the manner illustrated.

In practice, the metal component of the material is secured in place with the acoustic pads positioned within their receptacles, and then the plaster is applied with a trowel or the like according to accepted methods. In order that the perforate surfaces 11 will not be obstructed by plaster, even though they are used as screeds in leveling off the finished surface, they are covered with a thin paperlike material 20 which may be peeled or soaked off after the plaster has set. This material may be durable paper secured in place with a water soluble adhesive or may be Cellophane, holland, or any suitable moisture resistant strip secured with a pressure sensitive gum of the type which permits of its removal by peeling.

When the plaster has been applied, the thin strip which covers and protects the perforations 14 is removed and as its thickness is negligible the resultant surface has the appearance of a perfect plane which when painted or tinted is enhanced in appearance by the spaced strips of dots formed by the perforations 14 which extend throughout the entire length of the surface.

The manner of securing the metal in place may vary with the type of construction of the building in which it is to be used. In Figs. 1 and 2 it is shown in place as a ceiling supported by metal furring channels, one of which is indicated at 22. Wire, as shown at 23, may be passed over the channels and through the plaster key perforations 19. With the ends of the wire twisted and cut it will be entirely concealed by the plaster.

In a wood joist ceiling the metal may be quickly and inexpensively applied by nailing through the plaster perforations, and as illustrated in Fig. 3, distortion of the metal may be insured against by the use of collars 23a, the inside diameters of which receive the nails 24. These collars 23 are of a length to prevent the nails from being driven to a depth that will bend the metal and they may be provided with flanges 25 larger than the plaster key perforations through which the collars extend.

In securing the metal either to wood or metal joists or furring, the edges of the partitions 16-17 abut and are aligned by the structural members of which they are secured with the result that the exposed surface portions 11 are aligned in a plane parallel to the joists or furring and a perfectly flat wall or ceiling surface is therefore maintained if the underlying structure is properly aligned.

The metal components may be made in panels of any size and their size is determined by the sizes of sheets from which they are formed with consideration for convenience in handling and shipping. The sheets from which they are formed are sufficiently thin to permit of their being readily cut to reduce their size when the dimensions of a surface to be covered necessitates.

It is contemplated that for rooms of average

dimensions a plurality of the metal panels will be required to cover a ceiling. They are, therefore, formed for convenience in joining to give the appearance of a continuous surface. As shown in Fig. 5, the edges 27 of each panel will terminate as plaster key surfaces and will overlap to form a joint which may be secured by wire passing through the plaster key perforations and be entirely concealed by plaster. One end of each plaster key surface may be extended to form a tongue 28, and at their opposite ends these surfaces may have tabs 29 punched out to be bent through perforations 30 in the tongues of an adjacent sheet, as illustrated in Fig. 2. The tongues 28 are offset, as shown at 31 in Fig. 4, for a distance equal to the thickness of the metal so that the exposed abutting edges of the plates will be aligned in a common plane.

This alignment may be further insured by backing plates 32 which are bent to fit within the receptacles which contain the acoustic material and retained in place by pins or nails 33 passed through perforations 34 provided for this purpose. Both ends of the nails so used are disposed in the plaster channels so that the plaster secures them against removal and conceals them from view.

A plurality of panels are used to cover a surface and positioned with their ends abutting and overlapping in the manner described and with their side edges overlapping. As the corners of the panels would normally overlap with adjacent panels at the sides and ends there would be four thicknesses of metal at each corner. To prevent this bulk of metal and the consequent misalignment of the panels both of the edge sections 27, as illustrated in Fig. 5, are formed without the tongues 28, and one of these sections is cut away, as shown at 28a, for an area equal in size to one of the tongues 28. Thus, when the panels are placed together there are but two thicknesses of metal at each of the overlapping corners.

With the present invention an acoustically treated wall or ceiling surface of fine quality may be made at relatively low cost because of the fact that the acoustical material forms a part of the wall structure itself. The metal component serves and is applied much in the manner of ordinary metal lath and saves the cost of lath. The plaster required is less than for a conventional plaster wall and as it is in narrow strips extended cracks are unlikely to occur. The plane hard surface is easily decorated and cleaned and it presents an unusually neat and attractive appearance.

Having thus described and illustrated my invention, what I claim and wish to secure by Letters Patent is:

1. Acoustical material comprising a thin sheet of relatively rigid material formed to present a surface of alternate channels and ridges, said ridges presenting planar perforate surfaces, and a filling of plastic material in the channels to the plane of the ridge surfaces to present an exposed surface of alternate perforate and non-perforate areas.

2. Acoustical material comprising a thin sheet of relatively rigid material formed to present a surface of alternate channels and ridges, said ridges presenting planar perforate surfaces, strips of sound absorbing material supported behind and concealed by said ridges, and a filling of plastic material in the channels to the plane of the ridge surfaces to present an exposed surface of alternate perforate and non-perforate areas.

3. Acoustical material comprising a metal

plate formed to provide alternate channels and ridges, the surfaces of said ridges lying in a plane and being perforate, and a temporary covering of paperlike material on the perforate surfaces to protect them during the filling of the channels with a plastic material.

4. Acoustical material comprising a metal plate formed to present alternate channels and ridges, said ridges being perforated and concealing sound absorbing material, said channels having perforations to form a keying surface, and a plaster filling in said channels.

5. Acoustical material comprising a metal plate formed to present alternate channels and ridges, said ridges being perforated and concealing sound absorbing material, and said channels having perforations to form a keying surface for a plaster filling and means disposed within the channels and adapted to be concealed by the plaster filling for securing the plate in place in a building.

6. An acoustical surface composed of strips of plaster and exposed perforate metal alternately arranged to provide a plane surface, and a sound absorbent concealed by the perforate metal.

7. An acoustical surface formed of sheet material bent to form elongated areas on alternately high and low planes, plaster covering the low planes and finished to the level of the high planes, said high planes being perforate, and a

sound absorbent material concealed behind them.

8. An acoustical surface formed of sheet material bent to form elongated areas on alternately high and low planes, plaster covering the low planes and finished to the level of the high planes, said high planes being perforate, and a sound absorbent material concealed behind them and strips of paperlike material temporarily covering the perforate surfaces to protect the perforations during their use as screeds in levelling the plaster.

9. An acoustical surface comprising a sheet of material formed to present ridges and channels, said ridges having co-planar perforate surfaces, sound absorbing material concealed by said perforate surfaces, and a filling of plastic material in said channels finished to the level of said perforate surfaces.

10. An acoustical surface comprising a sheet of material formed to present ridges and channels, said ridges having co-planar perforate surfaces, and being arranged alternately with said channels to provide a uniform pattern over the entire surface, sound absorbing material supported adjacent to and concealed by said perforate surfaces, and a filling of plastic material in said channels finished to the level of said perforate surfaces.
